UNITED STATES PATENT OFFICE.

CHARLES J. COOPER, OF CHICAGO, ILLINOIS.

IMPROVEMENT IN LEATHER-CREASING MACHINES.

Specification forming part of Letters Patent No. **222,385**, dated December 9, 1879; application filed May 31, 1879.

To all whom it may concern:

Be it known that I, CHARLES J. COOPER, of Chicago, in the county of Cook and State of Illinois, have invented new and useful Improvements in Leather-Creasing Machines; and I declare the following to be a full, clear, and exact description thereof, which will enable others skilled in the art to which my invention appertains to make and use the same, reference being had to the accompanying drawings, which form a part hereof, and in which—

Figure 3 represents a vertical section of part of a leather-creasing machine embodying my invention. Fig. 1 represents an end view from the right of Fig. 3. Fig. 2 represents an end view from the left of Fig. 3; and Figs. 4 and 5 represent vertical views of two styles of creases, one taken on a plane parallel, and the other at right angle, to the line of the axis of Fig. 3.

Like letters of reference indicate like parts.

My invention relates to that class of machines employed in creasing harness; and it consists in the construction and combination of the several parts, as hereinafter described and claimed.

The circular creasers or dies heretofore used in leather-creasing machines could not be readily and conveniently set so as to be adapted to crease leather of different widths; and the object of my invention is to provide a machine that will accomplish that result.

In the drawings, O represents a flanged hollow shaft or feathered sleeve, which is secured upon a mandrel. (Not shown.) A recess or chamber, C, is sunk into flanges A A', into which may be placed one or more washers, as shown at W W' in Fig. 1. Against the washers are placed creasers B B' of the same

or different form or pattern, and they may be in direct contact or held apart by any suitable packing. Adjusting-screws S S are passed through the flange A and holes in washers W and creasers I, and are received by the female threads cut in the last creaser B. By working said screws the creasers I B, together with such others as may be interposed between them, may be drawn nearer to or set farther from the flange A, and securely held in the desired position by the set-screws J, which are made to press upon the washer W after the creasers are adjusted by the screws S. Upon the sleeve O is placed a feather-grooved sleeve, N, having a chambered flange, A', within which are placed washers W', and upon said sleeve O and in contact with washers W' are placed creasers I' and B' similar to and facing the creasers of flange A.

The sleeve N is provided with feathering-grooves E, which fit the feather F of shaft O, and may be readily moved to and fro and secured for any desired width of leather by the binding-screw K. A wooden or other roller, R, upon the shaft L, presses the leather down upon the creasers I B and I' B', and may be regulated by any known method.

Having thus described my invention, what I claim as new, and desire to secure by Letters Patent, is—

In a leather-creasing machine, the combination, with the flanged sleeves O and N, of the creasers B I and B' I', adjusting-screws S, and set-screws J, substantially as and for the purpose specified.

CHARLES J. COOPER.
